UNITED STATES PATENT OFFICE

148,065

DESIGN FOR A CHAIR

Harry Harris, Los Angeles, Calif.

Application January 26, 1946, Serial No. 126,010

Term of patent 3½ years

(Cl. D15—1)

To all whom it may concern:

Be it known that I, Harry Harris, a citizen of the United States and residing at Los Angeles, in the county of Los Angeles, State of California, have invented a new, original, and ornamental Design for a Chair, of which the following is a specification, reference being had to the accompanying drawing, forming part thereof, in which:

Fig. 1 is a front elevational view of a chair showing my new design;

Fig. 2 is a view in side elevation;

Fig. 3 is a plan view; and

Fig. 4 is a perspective view of a fragmentary end portion of the chair.

The characteristic features of my design reside in the portions shown by means of full lines in the drawing.

I claim:

The ornamental design for a chair, substantially as shown and described.

HARRY HARRIS.
